Primary Examiner — Michelle E. Wilson

(57) **CLAIM**

I claim the ornamental design for a microwave oven rack, as shown and described.

DESCRIPTION

FIG. 1 is a Perspective view of a microwave oven rack showing my new design;

FIG. 2 is a Front view of the microwave oven rack as shown in FIG. 1;

FIG. 3 is a Back view of the microwave oven rack as shown in FIG. 1;

FIG. 4 is a Right-side view of the microwave oven rack as shown in FIG. 1;

FIG. 5 is a Left-side view of the microwave oven rack as shown in FIG. 1;

FIG. 6 is a Top view of the microwave oven rack as shown in FIG. 1; and,

FIG. 7 is a Bottom view of the microwave oven rack as shown in FIG. 1.
